PEN

Emil Hechtle, Oradell, N.J., assignor to
Radiant Pen Corp.

Filed Jan. 4, 1960, Ser. No. 58,897

Term of patent 14 years

(Cl. D74—17)

FIG. 1 is an exploded side elevational view of a pen showing my new design;

FIG. 2 is another side elevational view thereof as it appears in assembled position and with the ball point projected;

FIG. 3 is a front elevational view thereof;

FIG. 4 is a rear elevational view of the cap portion;

FIG. 5 is an enlarged bottom plan view thereof rotated at an angle of 180 degrees; and

FIG. 6 is an enlarged transverse sectional view taken on the line 6—6 of FIG. 1.

The dominant feature of my design resides in the pen disclosed of the specific oversized clip portion integrally molded with the cap, all as shown.

I claim:

The ornamental design for a pen, substantially as shown and described.
